LIGHTING TORCH

Frank Andres, Carteret, N. J., assignor to Foster Wheeler Corporation, New York, N. Y., a corporation of New York

Application April 8, 1947, Serial No. 740,041

12 Claims. (Cl. 158—10)

1

The present invention relates to lighting torches and more particularly to a lighting torch for lighting the firing means of a furnace.

This invention provides a lighting torch which is so constructed that it will not be extinguished by air currents in a furnace when the torch is being used to light the burner or burners of said furnace.

The invention also provides a lighting torch of few parts which may be readily assembled and in which the wick is guarded from contact with surrounding objects.

The invention will be understood from the following description when considered in connection with the accompanying drawing forming a part thereof and in which:

Fig. 1 is an elevational view of the lighting torch of the present invention;

Fig. 2 is a transverse sectional view taken on the line 2—2 of Fig. 1;

Fig. 3 is a longitudinal sectional view taken on the line 3—3 of Fig. 2, and

Fig. 4 is a view similar to Fig. 1 but of another embodiment of the invention in longitudinal section.

Like characters of reference refer to the same parts throughout the several views.

Referring to the drawing, the torch has a cylindrical tubular metallic shield 10 lined on the inner periphery thereof with a wick comprising, as shown, an asbestos lining 11 secured to the shield in any desired manner. A plurality of widely spaced, relatively small diameter annular ports 12 extend through the shield and through the wick and provide air inlets through which air passes to the interior of said shield. For example, when a shield comprising a tube having an outside diameter of 1½" and a length of 3" is used, the ports 12 would be ¾" in diameter and arranged in a plurality of rows extending axially of the tube, the rows being spaced about 60° apart. Three ports would be spaced from one another approximately 1½" apart in each of the alternate rows, the opposite end ports of said alternate rows being spaced 1½" from the adjacent end of the shield. Two ports would be spaced from each other in the rows intermediate said alternate rows and would be in alignment with the spaces between the ports in said alternate rows.

One end of the shield 10 is open, while a circular washer 16 is secured in a fluid-tight manner within the shield adjacent the opposite end thereof, the washer 16 having an outer diameter which is substantially the same as the inner diameter of shield 10. Washer 16, as shown, is secured to the shield by means of welding 17.

Mounting member or stud 18 having external threads 19 projects through washer 16 and extends outwardly of the shield 10, the stud hav-

2

ing a flange 20 secured to the inner end thereof by welding 21 which flange is adapted to bear against the washer 16. Stud 18 is secured in position in relation to the shield 10 by a nut 22 which engages the external threads 19 and bears against the outer surface of washer 16. The nut 22 is drawn into such position that it bears against said outer surface of the washer 16 and causes the flange 20 to bear tightly against the inner surface of said washer in a fluid-tight manner. Stud 18 has a screw-threaded passage 23 in the end thereof extending outwardly of the shield which passage is adapted to receive one end of an elongated handle 24 threaded at 24' so as to engage the threads of the passage 23.

Another wick, wick 29, of the lighting torch of the present invention comprises a rod 25 the inner end of which is threaded at 26 to engage screw-threads in a passage 27 in the inner end of stud 18. The outer end of rod 25 has a flange 28 secured thereto. Asbestos rope 29' is spirally wound on rod 25. The inside diameter of the shield 10 and of the wick 11 is greater than the outside diameter of the wick 29 so that a chamber 40 is formed between wicks 11 and 29 which chamber receives air through the ports 12.

In operation, the asbestos rope 29' of the wick 29 and wick 11 are saturated with a combustible fluid and lighted, combustion being supported by air in the chamber 40 which air has entered said chamber through the ports 12. Since the ports 12 in the shield 10 are of relatively small diameter, the air currents within a furnace will not extinguish the wicks, the wicks being protected from said currents by the shield.

The embodiment of the invention illustrated in Fig. 4 is somewhat similar to that shown in Figs. 1 to 3 except that a combustible fluid is continuously fed to the wick 29. In Fig. 4, the handle 30 comprises a tubular member which, like the handle 24 of Fig. 1, is threaded at one end thereof into passage 23 of stud 18. At the opposite end thereof, handle 30 is in communication in a fluid-tight manner with a supply line 31 through which combustible fluid is introduced into the handle. The wick support 32 is similar to the rod 25 of Fig. 1 except that support 32 is tubular and closed at outer end 33 thereof. Inner end 34 of support 32 is threaded into passage 21 of stud 18 so that the passage within the support communicates with the interior of handle 30 through passage 27 so that said support will receive combustible fluid. Support 32 has a plurality of perforations 36 through the outer surface thereof and in communication with the passage therein so that combustible fluid is fed to asbestos rope 29'. With the structure shown in Fig. 4, combustible fluid can continuously be fed to asbestos rope 29' so that the

torch may be maintained lighted for long periods of time.

Since changes may be made in the form, location and relative arrangement of the several parts of the device disclosed without departing from the principles of the invention, it will be understood that the invention is not to be limited excepting by the scope of the appended claims.

What is claimed is:

1. A lighting torch comprising a handle, a wick extending from one end of the handle, another wick surrounding the first-mentioned wick in spaced relationship thereto thereby forming a chamber between said wick and said other wick, and a shield surrounding the wicks except at one end thereof, the shield and said other wick having a plurality of spaced openings therethrough, the openings being of such size, such number and so spaced from one another that sufficient air for combustion within said chamber but insufficient to extinguish said combustion is admitted to the chamber through said openings.

2. A lighting torch comprising a handle, a wick extending from one end of the handle, another wick surrounding the first-mentioned wick in spaced relationship thereto thereby forming a chamber between said wick and said other wick, and a shield surrounding the wicks except at one end thereof, the shield and said other wick having a plurality of spaced openings therethrough, the openings being of such size, such number and so spaced from one another that sufficient air for combustion within said chamber but insufficient to extinguish said combustion is admitted to the chamber through said openings, both of the wicks being entirely contained within the shield.

3. A lighting torch comprising a wick, a tubular shield surrounding said wick in spaced relationship thereto, said tubular shield being open at one end thereof and closed at the end opposite said one end, a wick lining lining the inner periphery of the shield, the shield and said wick lining surrounding the wick in spaced relationship thereto thereby forming a combustion chamber within the shield, the shield and the lining having a plurality of openings therethrough, the openings being of such size, such number and so spaced from one another that sufficient air for combustion within said chamber but insufficient to extinguish said combustion is admitted to the chamber through said openings, and a handle for said torch connected to the shield.

4. A lighting torch comprising a wick, a tubular shield surrounding said wick in spaced relationship thereto, said tubular shield being open at one end thereof and closed at the end opposite said one end, a wick lining lining the inner periphery of the shield, the shield and said wick lining surrounding the wick in spaced relationship thereto thereby forming a combustion chamber within the shield, the shield and the lining having a plurality of openings therethrough, the openings being of such size, such number and so spaced from one another that sufficient air for combustion within said chamber but insufficient to extinguish said combustion is admitted to the chamber through said openings, and a handle for said torch mounted at and extending from said opposite end of the shield.

5. A lighting torch comprising a wick, a tubular shield surrounding said wick in spaced relationship thereto, said tubular shield being open at one end thereof and closed at the end opposite said one end, a wick lining lining the inner

periphery of the shield, both the wick and the wick lining being entirely contained within said shield, the shield and said wick lining surrounding the wick in spaced relationship thereto thereby forming a combustion chamber within the shield, the shield and the lining having a plurality of openings therethrough, the openings being of such size, such number and so spaced from one another that sufficient air for combustion within said chamber but insufficient to extinguish said combustion is admitted to the chamber through said openings, and a handle for said torch mounted at and extending from said opposite end of the shield.

15 6. A lighting torch comprising a tubular shield, a wick lining lining the inner periphery of the shield, said shield being open at one end thereof and having an end wall closing the end thereof opposite said one end, mounting means secured in relationship to said end wall in a fluid-tight manner, a handle attached to said mounting means and extending outwardly and away from the shield, a wick secured to the mounting means, said wick projecting inwardly into the shield, the shield and said wick lining surrounding the wick in spaced relationship thereto thereby forming a combustion chamber within the shield, said shield and lining having a plurality of openings therethrough, the openings being of such size, such number and so spaced from one another that sufficient air for combustion within said chamber but insufficient to extinguish said combustion is admitted to the chamber through said openings.

30 7. A lighting torch comprising a tubular shield, a wick lining lining the inner periphery of the shield, said shield being open at one end thereof and having an end wall closing the end thereof opposite said one end, a screw-threaded stud extending through said end wall and projecting from opposite sides thereof, the stud having a screw-threaded passage extending axially therein and inwardly from the opposite ends thereof, means operatively associated with the studs and positioned to engage the inner surface of the wall in a fluid-tight manner, a nut operatively associated with the stud and adapted to engage the outer surface of the wall in a fluid-tight manner, a handle screw-threaded at one end thereof, said threads engaging the internally threaded portion of the stud in the end thereof projecting outwardly of said end wall, a wick comprising a member having screw threads thereon adapted to engage the screw-threaded passage in the inner end of the stud and project inwardly into the shield, both the wick and the wick lining being entirely contained within said shield, the shield and said wick lining surrounding the wick in spaced relationship thereto thereby forming a combustion chamber within the shield, said shield and lining having a plurality of openings therethrough, the openings being of such size, such number and so spaced from one another that sufficient air for combustion within said chamber but insufficient to extinguish said combustion is admitted to the chamber through said opening.

35 8. A lighting torch comprising a wick, a tubular shield surrounding said wick in spaced relationship thereto, said tubular shield being open at one end thereof and closed at the end opposite said one end, an asbestos lining lining the inner periphery of the shield, the shield and said lining surrounding the wick in spaced relationship thereto thereby forming a combustion chamber within the shield, the shield and the

lining having a plurality of openings therethrough, the openings being of such size, such number and so spaced from one another that sufficient air for combustion within said chamber but insufficient to extinguish said combustion is admitted to the chamber through said openings, and a handle connected to the shield.

9. A lighting torch comprising a metallic, cylindrically-shaped tubular shield, an asbestos lining lining the inner periphery of the shield, said shield being open at one end thereof and having an end wall closing the end thereof opposite said one end, a screw-threaded stud extending through said end wall and projecting from opposite sides thereof the stud having a screw-threaded passage extending axially therein and inwardly from the opposite ends thereof, means operatively associated with the stud and positioned to engage the inner surface of the wall in a fluid-tight manner, a nut operatively associated with the stud and adapted to engage the outer surface of the wall in a fluid-tight manner, a wick comprising a member having screw threads thereon adapted to engage the screw-threaded passage in the inner end of the stud and project inwardly within the shield, a wick comprising a spirally wound asbestos rope on said member, a handle screw-threaded at one end thereof, said threads engaging the internally threaded portion of the stud in the end thereof projecting outwardly of said end wall, both the wick and the wick lining being entirely contained within said shield, the shield and said asbestos lining surrounding the wick in spaced relationship thereto thereby forming a combustion chamber within the shield, said shield and lining having a plurality of openings therethrough, the openings being of such size, such number and so spaced from one another that sufficient air for combustion within said chamber but insufficient to extinguish said combustion is admitted to the chamber through said opening.

10. A lighting torch comprising a handle having a fluid-tight passage therein, a wick extending from one end of the handle, said passage being in communication with the wick, another wick surrounding the first-mentioned wick in spaced relationship thereto thereby forming a chamber between said wick and said other wick, and a shield surrounding the wicks except at one end thereof, the shield and said other wick having a plurality of spaced openings therethrough, the openings being of such size, such number and so spaced from one another that sufficient air for combustion within said chamber but insufficient to extinguish said combustion is admitted to the chamber through said openings.

11. A lighting torch comprising a tubular shield, a wick lining lining the inner periphery of the shield, said shield being open at one end thereof and having an end wall closing the end thereof opposite said one end, mounting means secured in relationship to said end wall in a fluid-tight manner, a handle having a fluid-tight longitudinally extending passage therein, the handle being attached to said mounting means and extending outwardly and away from the shield, a wick comprising a tubular support projecting into the shield having a plurality of perforations therein, an asbestos rope helically wound on said support, the tubular support being secured at one end thereof to the mounting

means and in communication with the passage in said handle, the opposite end of the support being closed, the shield and said wick lining surrounding the wick in spaced relationship thereto thereby forming a combustion chamber within the shield, said shield and lining having a plurality of openings therethrough, the openings being of such size, such number and so spaced from one another that sufficient air for combustion within said chamber but insufficient to extinguish said combustion is admitted to the chamber through said opening.

12. A lighting torch comprising a tubular shield, a wick lining lining the inner periphery of the shield, said shield being open at one end thereof and having an end wall closing the end thereof opposite said one end, a screw-threaded stud extending through said end wall and projecting from opposite sides thereof the stud having a screw-threaded passage extending axially therein and inwardly from the opposite ends thereof, means operatively associated with the stud and positioned to engage the inner surface of the wall in a fluid-tight manner, a nut operatively associated with the stud and adapted to engage the outer surface of the wall in a fluid-tight manner, a handle having a fluid-tight longitudinally extending passage therethrough, said handle being screw-threaded at one end thereof, said threads engaging the internally threaded portion of the stud in the end thereof projecting outwardly of said end wall, a wick comprising a tubular support member screw-threaded at one end thereof, said screw-threads engaging the screw-threaded passage in the stud, said support communicating with the passage in the handle and projecting into said shield, the tubular support member being closed at the end opposite said one end and having a plurality of perforations therein, an asbestos wick helically wound on said support, both the wick and the wick lining being entirely contained within said shield, the shield and said wick lining surrounding the wick in spaced relationship thereto thereby forming a combustion chamber within the shield, said shield and lining having a plurality of openings therethrough, the openings being of such size, such number and so spaced from one another that sufficient air for combustion within said chamber but insufficient to extinguish said combustion is admitted to the chamber through said opening.
